Attorney

UNITED STATES PATENT OFFICE.

JOHN SEWELL, OF BOWDON, GEORGIA.

IMPROVEMENT IN PLOWS.

Specification forming part of Letters Patent No. 171,435, dated December 21, 1875; application filed September 18, 1875.

To all whom it may concern:

Be it known that I, JOHN SEWELL, of Bowdon, in the county of Carroll and in the State of Georgia, have invented certain new and useful Improvements in Plows; and do hereby declare that the following is a full, clear, and exact description thereof, reference being had to the accompanying drawings, and to the letters of reference marked thereon, making a part of this specification.

My invention relates to turning plows, having a slotted foot for the attachment of the mold-board, &c.; and it consists in the construction of a beveled bar with land-side attached thereto, and having pins and projections for holding the same firmly in place between the plow-foot and mold-board, as will be hereinafter more fully set forth.

In order to enable others skilled in the art to which my invention appertains to make and use the same, I will now proceed to describe its construction and operation, referring to the annexed drawing, in which—

Figure 1 is a side view of a plow embodying my invention. Fig. 2 is a rear elevation of the same. Figs. 3 and 4 are perspective views of the right and left hand beveled bars with the mold-board detached therefrom.

A represents an ordinary plow-beam, with handles B, and braces C supporting the handles. D D represent two curved metallic bars, connected together at their lower ends by means of a solid beveled toe, and running parallel with each other a short distance, and bolted on the sides of the plow-beam A at the rear end, thus forming, as it were, a curved slotted plow-foot. E is a beveled bar, curved to correspond with the curvature of the plow-foot.

This bar may be beveled either to the right or left, so as to admit of the attachment of either a right or left turning-plow mold-board,

and it has a land-side bar, F, attached to it at or near its lower end.

A suitable distance above the lower end, near the outer or narrow edge, is a pin, b, projecting from the under side, and another pin, d, projecting from the upper side. Above these pins there is a bolt-hole, e, through the bar, and at the upper end is a lug or projection, a, extending toward the rear. The mold-board G, whether the same be for right or left hand, has two holes, x y, corresponding, respectively, with the pin d and bolt-hole e.

When placing the parts together, the pin b of the beveled bar E is inserted in a hole in the toe of the plow-foot D, and the hole x in the mold-board is placed over the pin d, and the lug a between the bars D. A bolt, h, is then passed through the holes y and e, and between the bars D of the plow-foot, and a nut, i, screwed upon its end to fasten the parts firmly together.

By these means the plow can be easily changed from a right to a left turning plow, and vice versa, and other implements may be attached to the plow-foot.

Having thus fully described my invention, what I claim as new, and desire to secure by Letters Patent, is—

The curved beveled bar E, provided with land-side bar F, pins b d, hole e, and projection a, in combination with the slotted plow-foot D, having perforated toe, the mold-board G, with holes x y, and the bolt h, with nut i, all substantially as and for the purposes herein set forth.

In testimony that I claim the foregoing I have hereunto set my hand this 13th day of August, 1875.

JOHN SEWELL.
